Patented Jan. 24, 1922.

UNITED STATES PATENT OFFICE.

OLAFUR JONSSON OLAFSON, OF KANDAHAR, SASKATCHEWAN, CANADA.

CEMENT BLOCK AND WALL STRUCTURE.

1,404,473.

Specification of Letters Patent. Patented Jan. 24, 1922.

Application filed March 18, 1921. Serial No. 453,319.

To all whom it may concern:

Be it known that I, OLAFUR JONSSON OLAFSON, a subject of the King of Great Britain, and resident of the town of Kandahar, in the Province of Saskatchewan, Dominion of Canada, have invented certain new and useful Improvements in Cement Blocks and Wall Structure, of which the following is a specification.

10 This invention relates to improvements in cement blocks and the wall structure made therefrom, and the objects of the invention are to provide a simple and effective method by which cement blocks may be laid 15 with greater facility and by those unskilled in such work.

Further objects are generally to improve and simplify the construction of the blocks to better adapt them to perform the functions required of them.

Cement blocks are preferably held together by a mixture of Portland cement, which differs from mortar used in ordinary brick-laying, and the blocks require to be 25 laid with a comparatively thin layer or film of cementitious material between them. It is difficult to lay ordinary blocks properly without considerable experience, and this difficulty is overcome in the present invention by providing means whereby the proper amount of cement will be gaged and automatically spread between the surfaces which are to be cemented together. This purpose is accomplished by forming a receiving 30 groove or recess in the lowermost block and a rib in the uppermost block adapted to project therein and force the cementitious material therefrom and between the blocks, all as hereinafter more fully set forth and 40 described in the accompanying specification and drawings.

In the drawings:

Figure 1 is a perspective view of a section of a wall constructed in accordance with the 45 present invention.

Figure 2 is a plan view of a left hand corner, showing one course of the blocks.

Figure 3 is a plan view of a right hand corner showing a different course of the 50 blocks.

Figure 4 is a perspective view of one form of the corner block.

Figure 5 is a perspective view of the T-shaped blocks.

Figure 6 is a perspective view of the second form of corner blocks.

Figure 7 is a vertical sectional view showing the joints between the two blocks.

Figure 8 is a perspective view of the T-shaped block in inverted position.

In the drawings like characters of reference indicate corresponding parts in all the figures.

Referring to the drawings:

A indicates the T-shaped block constituting the side of the wall formed with a face portion 10 and a lateral portion 11 at right angles thereto, and extending from substantially the centre of the face portion, both the face portion and the lateral portion having a recess or groove 12 in the upper edge thereof and a rib 13 in the lower edge thereof adapted to fit the groove 12 provided in the upper edge of the block. The edge of the face portion is also formed with grooves 14 designed to co-operate with corresponding grooves 15 formed in the edge of the lateral portion to receive bonding material such as grouting, which may be poured in the grooves after the blocks have been laid 80 in position.

B indicates one form of corner member, and C, the opposite form of corner member, these members being laid alternately in the corner, as shown in the drawings. The 85 corner member B is of angular shape and is formed with grooves 16 in the upper surface and corresponding ribs 17 in the lower surface and formed with face portions 18 and 19, the ends of which are formed with a 90 groove 20 co-operating with a groove in the end of the member A to receive bonding material.

The corner member C is of angular shape and formed with a groove 21 in the upper 95 side and a rib 22 in the lower side adapted to fit the groove 18 in the corner member B below it. The corner member is also formed on the side with grooves 23 adapted with the grooves 14 to form recesses to receive the grouting material. The side faces on the member C do not project laterally as far as those on the member B, whereby it will be possible to break joints between the 100

side members in the different rows, as shown in Figure 1.

- The size of the grooves in the top of each block is such that, when the ribs of the 5 next block above are forced into the grooves, the grooves having previously been filled with cementitious material, or grouting, sufficient cementitious material, or grouting, will be caused to overflow from the groove 10 into the space between the blocks to form a proper binding medium between the blocks. In this way, the exact amount of material necessary may be forced into position between the blocks.
- 15 It will be observed that the T-shaped blocks A are laid back to back, and so constitute, substantially, rectangular air spaces in the wall, and at the same time provide a well and uniformly reinforced wall.
- 20 As many changes could be made in the above construction, and many apparently widely different embodiments of my invention within the scope of the claims, constructed without departing from the spirit 25 or scope thereof, it is intended that all mat-

ter contained in the accompanying specification and drawings shall be interpreted as illustrative and not in a limiting sense.

What I claim as my invention is:

A cement structure comprising corner 30 blocks and T - shaped blocks said corner blocks laid one above the other, the corner blocks being formed alternately with longer sides, a plurality of said T-shaped blocks having their faces extending in opposite 35 directions, the said corner blocks and T-shaped blocks being formed with grooved edges forming recesses to receive grouting material, and grouting material in said recesses, the said blocks being further formed 40 with grooves on their upper surface and ribs on their lower surface designed to enter the grooves of the blocks in the lower course.

In witness whereof I have hereunto set my hand in the presence of two witnesses.

OLAFUR JONSSON OLAFSON.

Witnesses:

THORSTINE INDRIDOSON,
ROGNER STEVENSON.
